RUSSELL I. RHODES, OF NORTH ATTLEBORO, MASSACHUSETTS, ASSIGNOR TO THE MASON BOX COMPANY, OF ATTLEBORO FALLS, MASSACHUSETTS, A CORPORATION OF MASSACHUSETTS

CIGARETTE CASE OR THE LIKE

Application filed June 21, 1929. Serial No. 372,606.

This invention relates to containers and pertains more particularly to improvements in cases for cigarettes or the like. The principal object of the invention is to provide an article of this class comprising a pair of separable sections, preferably hinged to swing together to enclose the contents of the container, each section preferably comprising a rigid marginal frame and a flexible covering so that the structure exhibits the desirable durability and shape-sustaining characteristics of a metal case, and also possesses certain of the flexible and soft-textured characteristics and advantages of economy in manufacture and lightness in weight of a case made entirely of leather, cloth or other flexible material.

A recommended embodiment of the invention is shown in the accompanying drawings, in which:

Fig. 1 is a plan view of a closed case constructed in accordance with the invention, with portions broken away;

Fig. 2 is a side elevation of the case in open position;

Fig. 3 is a transverse section taken on line 3—3 of Fig. 2;

Fig. 4 is a bottom view of the rigid frame; Fig. 5 is a fragmentary section illustrating a modification;

Fig. 6 is a bottom view of a lining frame employed in a further modification;

Fig. 7 is a top view of the covered lining frame;

Fig. 8 is a sectional view to reduced scale taken on line 8—8 of Fig. 7; and

Fig. 9 is an enlarged section similar to Fig. 3, but showing the optional form of framed lining.

The cigarette case chosen for the purpose of illustration comprises a pair of similar sections or compartments 6 suitably hinged as at 7 to swing apart, or to be pressed together and retained in closed positions by a snap catch 8 or other fastening. The cigarettes 9 may be carried within an envelope or pocket 10 mounted within the case in any desired manner, or in a pocket located in either or both of the case sections, so that they will be readily available when the case is open

and will be enclosed therewithin when the sections are snapped together. The precise structure and arrangement of the case hinge or catch, or of the cigarette pocket is not essential to the present invention.

Each of the sections 6 has a narrow marginal frame 11 preferably stamped from a thin sheet of metal or other suitably rigid material and transversely dished or bowed, as shown, or otherwise shaped to form a one-piece skeleton structure concavo-convex in cross section, bordering a central opening 12 and having an inturned margin 13 around its periphery. A padding strip 14 of felt or other soft fabric is preferably applied upon the surface of the frame over the opening 12, and a flexible covering 15 of leather, fabric or composition material is superposed on the pad 14 and folded over the outer edge 13, as indicated at 16 of Fig. 3. The margins of the pad 14 extend between the frame 11 and the covering 15 and hence serve as an intervening cushion which prevents contact between the covering and the sharp frame edge surrounding the opening 12, and thus obviates the formation of an objectionable ridge in the flexible covering, which would be likely to be cracked, rubbed thin, or discolored during use. A lining piece 17 covers the opening 12 on the inner side of the case section and preferably overlaps the edges of the covering. The several sheets may be secured to each other and to the frame 11 by a suitable adhesive or other fastening means, and the outer surface of the covering may be embossed or otherwise ornamented as desired.

In the form above described and as shown in Fig. 3, the pad margin terminates short of the outer edge 13 of the frame 11 and the outer covering 15 is folded over said edge, thereby providing a thin, unyielding base edge which abuts the corresponding base of the complementary section when the case is closed. The felt pad 14 may, however, lap over said edge as indicated at 18 in the modified structure shown in Fig. 5 to afford a somewhat cushioned surface and protect the covering from wear at the line of fold over the metal edge. In said modification an additional pad or filler 19 may be provided in

the opening 12 between the pad 14 and the lining 17.

In the optional arrangement shown in Figs. 6 to 9, the lining for the respective case sections comprises a rigid frame 19, preferably formed of a single piece of thin sheet metal to provide narrow sides and ends bordering a central opening 20, said sides and ends being transversely bowed or inclined, thereby 10 to furnish a dished framework of a size adapted to fit within the case section. The corners of the frame may be notched or recessed as at 21 to allow for suitable bending of its sides and ends, and the outer edges of 15 the ends may have recesses 22 and 23 to accommodate the hinge and catch members of the case compartments.

The flexible lining piece 24 is applied upon the inner, dished side of the frame 19 and is 20 preferably folded over the outer edges thereof, as at 25, and adhesively secured to the frame, so that the frame and lining may be united as a unit within the covered frame 11 of the case section. When the parts are 25 thus assembled, as shown in Fig. 9, the covered edges of the lining frame 19 preferably register with the covered edges of the frame 11, thereby providing a case having smooth, unbroken inner and outer surfaces, flexible 30 at its central portion, rigid covered edges of the lining frame 19 preferably register with the covered edges of the frame 11 and the openings 20 and 12 of the respective frames may also register with each other, so that 35 the resulting case section presents smooth, unbroken outer and inner coverings, flexible and yielding at their central portions yet rigid at their margins, and a substantially flat and hard composite base edge. The lining frame may be secured within the case compartment by cementing together the in-turned margins of the lining 24 and outer covering 15 or by other fastening means.

A case constructed in either of the forms 45 above described is simple and economical to manufacture, light in weight without sacrifice of adequate rigidity, compact and attractive in appearance, and well adapted for carrying in the pocket, being rigid as to its 50 essential shape and contour but soft and flexible as to its sides. The relatively deep compartments afforded by the permanently dished frames of the complementary sections provide ample space for cigarettes or other 55 articles which may be enclosed within the case. The depth and yielding coverings of the sections obviate crushing of the cigarettes, and the rigid abutting edges of the closed sections form a firm and secure closure 60 to prevent cigarette tobacco from sifting out of the container. It will be understood, however, that structural details may be varied to suit particular purposes without departing from the essence of this invention 65 as defined in the following claims.

I claim:

1. In an article of the class described, a case section comprising a narrow, rigid marginal frame bordering a central opening, and a covering of flexible sheet material extending 70 across the opening and folded over the outer edge of the frame, the frame being formed of thin sheet material and being concavo-convex in cross-section.

2. In an article of the class described, a case section comprising a narrow, rigid marginal frame bordering a central opening, the frame being formed from a sheet metal blank and being transversely dished on its inner 75 side and rounded on its outer surface, and a covering of flexible sheet material extending 80 across the opening and folded over the outer edge of the frame.

3. In an article of the class described, a case section comprising a narrow, one-piece, 85 metal frame bordering a central opening, the outer margins of the frame being transversely dished on its inner side and rounded on its outer surface, a covering of flexible sheet material extending over the opening and folded over the outer edge of the dished frame margins, a pad extending across the opening and between the frame and the covering, and a lining applied over the opening 90 and over the margins of the covering on the inner side of the frame.

4. In an article of the class described, a case section comprising a rigid, dished outer frame bordering a central opening, an outer covering of flexible sheet material extending 100 across the opening and folded over the outer edge of the frame, a rigid, dished inner frame bordering a central opening, and a flexible lining applied to the inner side of 105 said inner frame over said opening and being folded over the outer edge of said frame, the lined inner frame being secured within the covered outer frame.

5. In an article of the class described, a case section comprising a rigid, dished outer frame bordering a central opening, an outer covering of flexible sheet material extending 110 across the opening and folded over the outer edge of the frame, a rigid, dished inner frame bordering a central opening, and a flexible lining applied to the inner side of said inner frame over said opening and being folded 115 over the outer edge of said frame, the lined inner frame being secured within the covered outer frame, the outer covered margins of the respective frames fitting closely against each other with their outer edges in substantial registration.

6. In an article of the class described, a case section comprising a rigid, dished outer frame bordering a central opening, an outer covering of flexible sheet material extending 120 across the opening and folded over the outer edge of the frame, a rigid, dished inner frame bordering a central opening, and a flexible 125 lining applied to the inner side of said inner frame over said opening and being folded over the outer edge of said frame, the lined inner frame being secured within the covered outer frame, the outer covered margins of the respective frames fitting closely against each other with their outer edges in substantial 130 registration.

lining applied to the inner side of said inner frame over said opening and being folded over the outer edge of said frame, the lined inner frame being secured within the covered outer frame, the outer covered margins of the respective frames fitting closely against each other with their outer edges in substantial registration and the central openings in the two frames being approximately equal in size.

Signed by me at Attleboro Falls, Mass.,
Bristol County, this 14th day of June, 1929.

RUSSELL I. RHODES.
